FISH FRYING RANGE

Dean Hutchison, Sacramento, Calif., assignor to Dean
Industries, Ltd., Inglewood, Calif.

Filed Apr. 23, 1969, Ser. No. 16,861

Term of patent 7 years

Int. Cl. D7—04

U.S. Cl. D81—10

FIG. 1.

FIG. 3.

FIG. 4.

FIG. 2.

FIG. 5.

FIG. 6.

FIG. 1 is a front elevational view of the fish frying range;

FIG. 2 is a side elevational view of the fish frying range;

FIG. 3 is a top plan view of the fish frying range;

FIG. 4 is a rear elevational view of the fish frying range;

FIG. 5 is a front perspective view of the fish frying range; and

FIG. 6 is a rear perspective view of the fish frying range.

The side opposite to that shown in FIG. 2 is a mirror image thereof.

I claim:

The ornamental design for a fish frying range, as shown and described.
